INVENTOR.
Alfred Balmforth,
BY

Geo. P. Kimmel ATTORNEY.

UNITED STATES PATENT OFFICE.

ALFRED BALMFIRTH, OF MONTREAL, QUEBEC, CANADA.

GRATE.

Application filed June 10, 1924, Serial No. 719,199. Renewed June 2, 1925.

To all whom it may concern:

Be it known that I, ALFRED BALMFIRTH, a citizen of the Dominion of Canada, residing at Montreal, in the county of Hochelaga, Province of Quebec, Dominion of Canada, have invented certain new and useful Improvements in Grates, of which the following is a specification.

This invention relates to grates, more particularly to the bars thereof, and is designed primarily for use in the burning of low grade fuels, anthracite screenings and dust, saw-dust, coke breeze, etc., but it is to be understood that a grate set up from 10 grate bars, in accordance with this invention can be employed for any purposes wherein it is found applicable, and the invention has for its object to provide, in a manner as hereinafter set forth, a grate bar 15 constructed to burn economically the finely divided anthracite dust, screenings and what has been generally considered as refuse in furnaces generally, and by modifications and the manner of assembling, may be used 20 in household round pot furnaces, or under steam boilers for factory purposes.

A further object of the invention is to provide, in a manner as hereinafter set forth, ported grate bars that will answer 25 respectively for slow combustion fires, as in house heating furnaces, and for high combustion grates as in high pressure boilers for factory or power house work.

Many different kinds of grates have been 30 used in the past for the purpose of burning low grade anthracite fuels, but have been found inefficient through incomplete combustion or inability to obtain the required amount of steam or heat from a given 35 surface, both of which are caused by inability to obtain combustion over the entire grate surface. As there is an enormous supply of these low grade fuels which are at present 40 unsuitable for general use on account of difficulty of burning them satisfactorily, it is evident that any means whereby they may 45 be rendered available will be of material benefit, and to this end the primary object of the invention is to provide a grate composed of bars of suitable material and so 50 constructed that they will produce full and

even heat with finely divided fuels over the entire area of the furnace grate, due to the even distribution of air under slight pressure, discharged at an angle under the fuel 55 and at the surface of the grate.

A further object of the invention is to provide, in a manner as hereinafter set forth, a grate bar which when used in connection with a grate will prevent loss of 60 fine fuel through the grate into the ash pit before the fuel has been completely burned.

A further object of the invention is to provide, in a manner as hereinafter set forth, a grate bar so constructed that when 65 a plurality of bars are employed in connection with the grate, will not only prevent loss of fuel, but furthermore will interlock with each other in a manner to prevent, when one or more of the bars is broken, the 70 pulling out or dropping of a damaged bar or a portion thereof, under such conditions not interrupting the service which would be the case if the damaged bar or portion thereof would drop out of the grate or be removed therefrom.

Further objects of the invention are to provide, in a manner as hereinafter set forth, a grate bar, which is simple in its construction and arrangement, strong, durable, compact, readily assembled when used in connection with a grate, thoroughly efficient in its use, and comparatively inexpensive to manufacture.

With the foregoing and other objects in 85 view, the invention consists of the novel construction, combination and arrangement of parts, as hereinafter more specifically described and illustrated in the accompanying drawings, wherein is shown an embodiment 90 of the invention, but it is to be understood that changes, variations and modifications can be resorted to which come within the scope of the claims hereunto appended.

More specifically stated the invention in 95 its broad conception consists in constructing and arranging the grate bars to conjointly form draught slits disposed in directions oblique to the median lines of the bars, the said slits being preferably disposed in 100 opposite directions.

In the drawings wherein like reference

characters denote corresponding parts throughout the several views:

Figure 1 is a plan view of a plurality of grate bars in accordance with this invention, of the double ported type.

Figure 2 is a top plan view of a grate bar in accordance with this invention, of the double ported type.

Figure 3 is an inverted plan, of a grate bar in accordance with this invention, of the double ported type.

Figure 4 is a section on line 4—4, Figure 1.

Figure 5 is a section on line 5—5, Figure 2.

Figure 6 is a section on line 6—6, Figure 2.

Figure 7 is a section on line 7—7, Figure 1.

Figure 8 is a top plan view of a plurality of assembled grate bars in accordance with this invention, of the single ported type.

Figure 9 is a top plan view of the grate bar in accordance with this invention, of a single ported type.

Figure 10 is a side elevation of a grate bar in accordance with this invention, of a single ported type.

Figure 11 is a section on line 11—11, Figure 8.

Figure 12 is a section on line 12—12, Figure 8.

Figure 13 is a fragmentary view, in plan, of a plurality of assembled double ported grate bars of a modified form in accordance with this invention.

Figure 14 is a section on line 14—14, Figure 13.

Figure 15 is a section on line 15—15, Figure 13.

Referring to Figures 1 to 7 of the drawings, the bar is of substantial length and includes a pair of rectangular end portions 1, 2, of substantial height and thickness, and an intermediate portion referred to generally by the reference character 3.

The intermediate portion 3 is formed of a series of transverse parts 4 and a series of longitudinal parts 5. The parts 4, as well as the parts 5 are rectangular in contour, and the parts 4 extend in an opposite direction with respect to the parts 5. The width of the parts 5 is the same as the width of the end portions 1, 2, and are arranged in alignment therewith. The parts 4 extend lengthwise in a perpendicular direction with respect to the length of the parts 5, whereby the parts 4 will project beyond the sides of the parts 5. The parts 4 are alternately disposed with respect to the parts 5.

The upper surface of the parts 5 is plane throughout and arranged in alignment with the upper faces of the end portions 1, 2.

The upper face of each of the parts 4,

from the longitudinal center of the bar, inclines downwardly throughout in opposite directions, as at 6, 7.

The parts 5 are of less height than the parts 4, and the lower faces of the parts 5 are bevelled upwardly in opposite directions, as at 8, 9, but each of the bevels extends from a point removed from the longitudinal center of the bar and terminates at the sides thereof. The bevels 8, 9, are of materially less length than the length of the oppositely inclined surfaces 6, 7 of the parts 4.

Formed integral with the lower face of the parts 4, 5, centrally thereof, and also formed integral with the inner ends of the end portions 2, is a web 10, of materially less thickness than the thickness of the end portions 1, 2. The web gradually increases in height from each end thereof towards the center, as clearly shown in Figure 10. The web 10, centrally thereof, is enlarged, as at 11, for the purpose of reinforcing the same.

In Figure 1, the grate bars are indicated at 12, 13, 14 and 15, and the parts 4, 5 of the bar 12 are staggered with respect to the parts 4, 5 of the bar 13, and the parts 4, 5 of the bar 14 are staggered with respect to the parts 4, 5 of the bar 13. This arrangement is carried throughout when the grate is set up, that is to say each adjacent bar has its parts 4, 5, staggered with respect to the other bars.

When the bars are arranged in grate formation, the bevelled surfaces 8, 9 of the parts 5 of an intermediate bar overlap and are spaced from the inclined surfaces 6 and 7 of a pair of adjacent bars, as disclosed in Figure 4, thereby providing a pair of oppositely extending upwardly inclined air passages 16, 17.

When the bars are arranged in grate formation, there is associated with each end bar a locking bar, as indicated at 18, and the latter is formed of a pair of end portions 19, 20 and an intermediate portion 21. The locking bar 18 has its intermediate portion 21, at its inner side, provided with spaced projections 22 extending a substantial distance from the inner side of said intermediate portion 21.

The intermediate portion 21 has its inner face, at a plurality of spaced points, undercut, as at 23, and said undercut portions extend downwardly at an inclination and transversely of a part of the lower face of the intermediate portion 21. The upper face of the intermediate portion 21 is formed with a series of spaced depressions which extend towards the inner side of the portion 21. The bottom of each of the depressions 24 is inclined, as at 25, and the upper face of an extension 22 forms a continuation of the inclined bottom 25, as indicated at 26. The inclined undercuts 23 are alternately

disposed with respect to the depressions 24 and when the locking bar 18 is mounted in position with respect to the outer bar of a plurality of grate bars, the projections 22 5 oppose the bevelled surfaces, but spaced therefrom, of the parts 5 of the outer bar 12. The undercuts 23 of the bar 18 oppose and are spaced from the inclined surfaces 7 of the outer grate bar 12. The projections 26, 10 in connection with the bevels 8 of the bar 12, form outwardly extending and upwardly inclined air passages 27. The top walls of the undercuts 23, in connection with the inclined surfaces 7, of the grate bar 12, provide inwardly extending and upwardly inclined air passages 28.

The locking bar 18 is provided with a depending web 29 formed integral with the end portions 19 and 20 and with the intermediate 20 portion 21.

The grate bar shown in Figures 1 to 7, is what may be termed a double ported type, and when a series of the double ported grate bars is assembled in a manner as stated, the 25 air currents meet and alternate at frequent intervals to prevent formation of dead areas, where low combustion rates with attention at long intervals are needed, as in round pot furnaces for house heating purposes.

In the form of grate bar as disclosed in Figures 8 to 12, the bar is of substantial length and consists of a pair of rectangular portions 29', 30, and an intermediate 35 portion 31. The end portions and intermediate portion are connected together by a web 32. The intermediate portion is of materially less height than the end portions 29' and 30. The intermediate portion 31 has each side thereof provided with spaced projections formed with a downwardly inclined upper face. The projections at one side of the intermediate portion 31 are indicated at 33, and the projections on the other side of 40 the intermediate portion 31 are indicated at 34. The projections 33 are alternately disposed with respect to the projections 34 on the intermediate portion 21. The upper face of the intermediate portion 31 is formed 45 with two series of spaced depressions. The depressions of one series extend in an opposite direction with respect to the other series and said depressions extend from the longitudinal center of the intermediate portion 50 31. The depressions of one series are indicated at 35 and the depressions of the other series at 36. The depressions 35 are alternately disposed with respect to the depressions 36. The bottoms of the depressions 55 35 are inclined downwardly as at 37, and the upper face 38 of the projections 33 forms a continuation of the bottoms 37 of the depressions 35. The bottoms 39 of the depressions 36 are inclined, and the upper face of 60 the projections 34, as indicated at 40, forms

a continuation of the bottoms 39 of the depressions 36.

The lower face of the intermediate portion 31 is provided with two series of spaced undercuts and with the undercuts of one 70 series extending in an opposite direction with respect to the undercuts of the other series. The undercuts of one series are indicated at 41, and the undercuts of the other series at 42. The undercuts 41 and 42 extend upwardly at an inclination and from a point at one side of the longitudinal center of the intermediate portion 31. The undercuts 41 are alternately disposed with respect to the undercuts 42.

The construction of grate bar disclosed in Figures 8 to 12 is of the single ported type and in Figure 8 a series of single ported bars is shown assembled, and which are indicated at 43, 44, 45 and 46. The locking 80 bar for the single ported bars is indicated at 47 and is of the same construction as the locking bar 18 and associates with the outer bar 43 of the series of grate bars, in the same manner as the bar 18 associates with the bar 90 12.

In the single ported bar construction the projections 33 of an intermediate bar associate with the undercuts 38 of an adjacent bar to provide an upwardly and outwardly 95 extending air passage 48. The projections 34 of an intermediate bar associate with the undercuts 42 of an adjacent bar to provide an inwardly extending and upwardly inclined air passage 49.

When the single ported bars are arranged in grate-like form, there is provided a large number of angular blast openings or ports alternating to right and left across adjacent bars at frequent intervals and causing the 100 opposing air currents to pass each other when high combustion rates are required as in high pressure boilers for power plants and factory purposes.

In the single ported bars the air is discharged from all ports of the same hand in the same plane, and the reversing currents pass each other making their entire grate alive, but in the double ported bars, the air currents are opposed and meet in the center 110 of the bar, forming alternative live and dead blocks. The air meeting at the center of the live block is diverted over dead blocks adjoining, and in this manner the whole grate is made alive.

In the modified form shown in Figures 13, 14 and 15, the construction is somewhat similar to that shown in Figures 4 to 6, with this exception, that the parts 50, which correspond to the parts 4, have their oppositely 125 extending inclined surfaces 51 and 52 of less length and greater pitch than the inclined surfaces 6 and 7 and further whereby the side edges 53 of the parts 50 are of greater height than the side edges of the parts 4.

Further, the bevelled surfaces 54, 55 of the parts 56, which correspond to the parts 5, are of less length and greater pitch than the bevelled surfaces 8, 9, and further the part 56 has vertical side edges 57 which oppose and are of greater height than the side edges 53 of the parts 4. Otherwise than that as stated, the construction is the same. The reference character 58 denotes a locking bar, 10 which is constructed similar to the bar 18.

When the double ported or single ported bars are set up in grate-like form, they have portions thereof abutting against each other and which in connection with the manner of 15 setting up the ports prevents loss of fine fuel through the grate into the ash pit before it has been completely burned. Then further the air currents will materially assist in preventing the escape of the fuel. 20 When the double ported bars are assembled in grate-like form the parts 6 will engage with the underside of the parts 5, and the bars will then be locked together and cannot fall into the ash pit, nor be pulled out of 25 place when cleaning fires, even if broken, unless a locking bar is first removed. This same arrangement applies to the projections 33 and 34 with respect to the parts of the intermediate part 31 provided with the undercut 30 41 and 42.

What I claim is:—

1. A grate bar comprising a substantially elongated body formed of a pair of end portions and an intermediate portion, said intermediate portion having its upper face formed with oppositely disposed spaced downwardly inclined surfaces extending at right angles with respect to the length of the bar, and said intermediate portion further 35 having its lower face provided with oppositely disposed spaced upwardly extended bevel surfaces extending at right angles with respect to the length of the bar and alternately arranged with respect to the said inclined surfaces. 40

2. A grate bar comprising a substantially elongated body formed of a pair of end portions and an intermediate portion, said intermediate portion having its upper face formed with oppositely disposed spaced downwardly inclined surfaces extending at right angles with respect to the length of the bar, and said intermediate portion further having its lower face provided with oppositely disposed spaced upwardly extended bevel surfaces extending at right angles with respect to the length of the bar and alternately arranged with respect to the said inclined surfaces, said inclined surfaces of 50 greater length than said bevelled surfaces and projecting beyond and laterally with respect to the outer termini thereof. 55

3. A grate bar comprising a substantially elongated body formed of a pair of end portions and an intermediate portion, said in-

termediate portion having its upper face formed with oppositely disposed spaced downwardly inclined surfaces extending at right angles with respect to the length of the bar, said intermediate portion further having its lower face provided with oppositely disposed spaced upwardly extended bevel surfaces extending at right angles with respect to the length of the bar and alternately arranged with respect to the said inclined surfaces, and a depending web integral with and of less thickness than said intermediate portion. 70

4. A grate bar comprising a substantially elongated body formed of a pair of end portions and an intermediate portion, said intermediate portion having its upper face formed with oppositely disposed spaced downwardly inclined surfaces extending at right angles with respect to the length of the bar, said intermediate portion further having its lower face provided with oppositely disposed spaced upwardly extended bevel surfaces extending at right angles with respect to the length of the bar and alternately arranged with respect to the said inclined surfaces, said inclined surfaces of greater length than said bevelled surfaces and projecting beyond and laterally with respect to the outer termini thereof, and a depending web integral with and of less thickness than 80 85 90 95

5. A grate bar comprising a substantially elongated body formed of a pair of end portions and an intermediate portion, said intermediate portion having its upper face formed with oppositely disposed spaced downwardly inclined surfaces extending at right angles with respect to the length of the bar, and said intermediate portion further having its lower face provided with oppositely disposed spaced upwardly extended bevel surfaces extending at right angles with respect to the length of the bar and alternately arranged with respect to the said inclined surfaces, the parts of said intermediate portion having the inclined surfaces of a length to extend below and in spaced relation with respect to the bevelled surfaces of an adjacent bar to provide angularly disposed air passages and further to interengage with such adjacent bar. 100 105 110 115

6. A grate bar comprising a substantially elongated body formed of a pair of end portions and an intermediate portion, said intermediate portion having its upper face formed with oppositely disposed spaced downwardly inclined surfaces extending at right angles with respect to the length of the bar, and said intermediate portion further having its lower face provided with oppositely disposed spaced upwardly extended bevel surfaces extending at right angles with respect to the length of the bar and alternately arranged with respect to the 120 125 130

said inclined surfaces, said end portions of greater height than said intermediate portion.

7. A series of grate bars, the adjacent bars of which form shallow draft interstices therebetween, said interstices extending alternately in opposite directions substantially

throughout the length of the bars and disposed in directions oblique to the upper surface of the grate formed by the series of 10 bars.

In testimony whereof, I affix my signature hereto.

ALFRED BALMFIRTH.
